(57) **CLAIM**

The ornamental design for extensible shelf divider, as shown and described.

DESCRIPTION

FIG. 1 is a perspective view of an extensible shelf divider showing our new design;

FIG. 2 is a right side elevational view thereof;

FIG. 3 is a left side elevational view;

FIG. 4 is a top plan view thereof;

FIG. 5 is a bottom plan view thereof;

FIG. 6 is an end view toward one end thereof;

FIG. 7 is an end view toward the opposite end thereof;

FIG. 8 is a left elevational view showing the preferred design in an extended condition from that shown in FIG. 3;

FIG. 9 is an enlarged perspective view of the preferred design of the extensible shelf divider as installed on a shelf;

FIG. 10 is a perspective view of another, second preferred design;

FIG. 11 is a right side elevational view of the second preferred design;

FIG. 12 is a left side elevational view of the second preferred design;

FIG. 13 is a top plan view of the second preferred design;

FIG. 14 is a bottom plan view of the second preferred design;

FIG. 15 is an end view toward one end of the second preferred design;

FIG. 16 is an end view toward the opposite end of the second preferred design;

FIG. 17 is a left elevational view of the second preferred design in an extended condition from that shown in FIG. 12; and,

FIG. 18 is an enlarged perspective view of the second preferred design as installed on a shelf.

The broken lines shown illustrate environmental structure and form no part of the claimed design.
